BILLIARD TABLE OR THE LIKE

Richard G. Reineman, Covina, Calif., George H. Hart, Chicago, Ill., and George E. Schaefer, Muskegon Heights, Mich., assignors to Brunswick Corporation, Chicago, Ill., a corporation of Delaware

Filed Aug. 23, 1961, Ser. No. 66,471

Term of patent 14 years

(Cl. D34—3)

FIG. 1.

FIG. 2.

FIG. 3.

FIG. 4.

FIG. 5.

FIG. 1 is a perspective view of a billiard table or the like showing our new design;

FIG. 2 is a top plan view thereof;

FIG. 3 is a side elevation view thereof;

FIG. 4 is an end elevation looking at the left end of FIG. 3;

FIG. 5 is an end elevation looking at the right end of FIG. 3.

The dominant features of our design are shown in solid lines in the drawings.

We claim:

The ornamental design for a billiard table or the like, as shown and described.
